UNITED STATES PATENT OFFICE

170,973

CUTLERY CASE OR SIMILAR ARTICLE

Neal Goldman, New York, N. Y., assignor to The International Silver Co., Meriden, Conn., a corporation of Connecticut

Application October 13, 1952, Serial No. 21,819

Term of patent 14 years

(Cl. D58—12)

To all whom it may concern:

Be it known that I, Neal Goldman, a citizen of the United States of America, residing in the Borough of Manhattan, city of New York, county of New York, and State of New York, have invented a new, original, and ornamental Design for a Cutlery Case or Similar Article, of which the following is a specification, reference being had to the accompanying drawing, forming part hereof.

Figure 1 is a plan view of a cutlery case or similar article showing my new design.

Figure 5 is a perspective view of the other side of the cutlery case in open position.

The rear view not shown is the same as the front view shown.

I claim:

The ornamental design for a cutlery case or similar article, as shown and described.

NEAL GOLDMAN.
